UNITED STATES PATENT OFFICE.

ERNEST LENNOX DUNAND, OF LONDON, ENGLAND.

SCREEN FOR TELEPHONES OR THE LIKE.

Application filed December 8, 1926, Serial No. 153,242, and in Great Britain June 18, 1926.

The invention concerns a screen for use in conjunction with a telephone, or other table or desk article mounted upon or formed with a pedestal, column or equivalent.

5 The object is to provide a screen of a light nature, capable of an attractive appearance, and movably attached to the telephone or the like, so that, whilst normally it covers or obscures the same, it may be nevertheless easily 10 and quickly moved aside when the article is to be used or exhibited.

The said device is more particularly applicable to desk telephones of the pedestal or standard type, and such application will be 15 hereinafter referred to and illustrated.

Broadly the invention consists of a suitable screen of dimensions large enough to cover a telephone from one side, said screen being provided with means whereby it is or can be 20 pivotally attached to the pedestal of the telephone, and means to facilitate its movement on the desk, table or the like. When it is desired to use the telephone, the screen is swung in a circular fashion around the telephone (with the pedestal as an axis).

In order that the said invention may be more readily understood a sheet of drawings is appended hereto illustrating various embodiments described later, and in said drawings:-

Figure 1 is a sectional elevation of one form of screen attached to a pedestal telephone.

Figure 2 is a plan thereof.

35 Figure 3 is a view of a detail hereinafter referred to.

Figures 4 and 5 are diagrammatic views showing alternative forms of screens in section.

40 The screen may be of any desired shape, such as rectangular with or without the top or other edges scrolled or otherwise ornamented, and in horizontal section or plan it is preferably arcuate such as approximately 45 semi-circular as in Figures 1 or 2, or V-shape, or with more than two panels, or a plurality of facets. Or it may be hood-shaped as in Figures 4 and 5, or bowl-shaped (quarter-spherical), or otherwise according to taste. 50 In all the figures of the accompanying drawings the screen is indicated by the reference numeral 1.

55 Referring more particularly to Figures 1, 2 and 3, a substantially semi-circular screen is formed by covering a light wire frame with paper, silk, linen, leather or other suit-

able material, which may be applied thereto, having any suitable designs or printed work.

From a suitable part of the wire frame, such as a central vertical wire 9 as illustrated, or from one edge e. g. the bottom (not shown), there extends inwardly on the concave side, an arm or arms 2 which may be wire, twisted or not for rigidity, or a metal rod or band, and integral or not with the said frame, and which terminate in a pair of curved fingers 3 for gripping the pedestal 4— see the detail view Figure 3.

The bottom edge of the screen 1 is provided with a pair or more of runners, castors, wheels, slideable domed feet or other devices indicated by the numeral 5 to facilitate the screen's movement over the desk or the like.

In the hooded arrangement seen in Figure 5, the method of pivoting the screen 1 to the pedestal 4 is varied. The arm or arms 2 extending radially from the screen (as in previously described example) are replaced by the vertical support 6 terminating in the pivotal fingers 3, and a knob 7 can be used as 80 a securing nut. 8 indicates a counterbalancing device to facilitate easy movement of the screen. A ring 10 (see Figure 1) especially may be formed on or affixed to the screen in any suitable position to support the telephone 85 flex out of the way of the swinging movement of the screen.

I claim:

A screen for telephone instruments and other pedestal articles, comprising a fabric covered frame provided with a pair of horizontal parallel spacing arms of equal length disposed one above the other and both extending from a single vertical central frame member so as to be radial with respect to the pedestal, an integral U-shaped clip formed on the inner end of each of said arms for movably engaging the pedestal in such a manner as not to take the weight of the screen, and a horizontal member secured to the lower end of said central frame member and extending in concentric relation to said pedestal, said horizontal member carrying a pair of rollers disposed one at each side of the aforesaid vertical central frame member so that the upper parts of the rollers are concealed by the screen.

In testimony whereof, I have signed my name to this specification at London, England, this 11th day of November, 1926.

ERNEST LENNOX DUNAND.
